(57) **CLAIM**

The ornamental design for a belted track assembly, as shown and described.

DESCRIPTION

FIG. 1 is a top, front, left perspective view of a belted track assembly showing my new design;

FIG. 2 is a front perspective view thereof;

FIG. 3 is a rear perspective view thereof; and,

FIG. 4 is a top view thereof and wherein the bottom, right and left side views are identical with each depicting the repeating pattern of the lugged track surface and only the mounting position of the octagon tension adjustment cover varying.

1 Claim, 4 Drawing Sheets
